METHOD OF PROVIDING STRANDED STRUCTURES WITH FITTINGS

Otto J. Bratz, Adrian, Mich., assignor, by mesne assignments, to American Chain & Cable Company, Inc., a corporation of New York

Application April 9, 1935, Serial No. 15,405

23 Claims. (Cl. 29—148)

This invention relates to a method of providing flexible stranded wire structures with reinforcements or fittings and is described with particularity as to its application in providing the ends of a flexible helically coiled wire tubular casing with means for preventing uncoiling or spreading which means constitutes a sleeve or ferrule or attachment member for the end of the casing.

It is common practice to make coiled wire tubing primarily in continuous form and then to cut the tubing into desired lengths. Heretofore, it has been necessary to provide auxiliary clamping means to prevent the severed wires from springing and uncoiling until they could be secured permanently by a sleeve, ferrule or other binding means. My invention has for an object the provision of a method which dispenses with such auxiliary clamping means and simplifies the method of manufacturing flexible wire casings by providing a binding which may be applied at predetermined spaced points on the casing before the casing is severed and which is of such a character that it may be converted into a ferrule or its equivalent by a swaging operation either before or after the severing operation.

Other objects and advantages of my improved method will appear from the following description of my method with reference to a disclosure of several preferred embodiments of helically coiled wire tubular casings produced by my method, and thereafter the novelty and scope of my invention will be pointed out in the claims.

In the accompanying drawing:

Figure 1 is a view in side elevation and partly in section of one end of a stranded wire casing with a binding or reinforcement applied thereto in accordance with my method and before swaging;

Fig. 2 is a view in side elevation of both ends of a stranded wire casing with reinforcements applied thereto and swaged thereon in accordance with my method, one end of the casing being partly broken away to show structural details;

Fig. 3 is a view in cross-section taken substantially on the line 3—3 of Fig. 2;

Figs. 4 and 4a are plan and end views respectively of a reinforcement strip, illustrating the conformation of the inner face of the strip;

Fig. 5 is a view in side elevation and partly in section of one end of a stranded wire casing with a reinforcement applied thereto in accordance with my method, such reinforcement being of different section from that shown in Fig. 2;

Figs. 6 and 6a are plan and end views respec-

tively of the inner face of the reinforcement strip employed in the structure shown in Fig. 5;

Fig. 7 is a view in side elevation and partly in section of one end of a stranded wire casing reinforced with a metallic strip of different section from that shown in Figs. 2 and 5 and with a metallic sleeve swaged upon the reinforcement, in accordance with my method;

Figs. 8 and 8a are plan and end views respectively of the reinforcement strip shown in Fig. 7;

Fig. 9 is a view in side elevation and partly in section of one end of a stranded wire casing with reinforcement applied thereto and with one-half of a split clamp engaging such reinforced end of the casing, in accordance with my method;

Fig. 10 is an end view looking from the left hand side of Fig. 9 with both halves of the clamp applied to the casing; and

Figs. 11 and 12 are fragmental views in side elevation and partly in section of two other forms of flexible casing with a reinforcement swaged thereon in accordance with my method.

The flexible wire casing shown in Figs. 1 and 2 is of standard construction and comprises an inner layer 15 consisting of a helix of flat wire, the convolutions of the helix being slightly spaced apart so as to permit of flexing the helix about its axis. A second layer 16 which is applied directly upon the helix 15 comprises a series of contiguous wires coiled with a long pitch. An outer helix 17 serves to bind the wires of the second layer so that when the structure is flexed the wires of the second layer will be constrained to slide lengthwise relatively to each other, but will be maintained at all times in close contact. The outer helix 17 serves merely to retain the wires of the second layer 16 and consequently the convolutions of this helix are widely spaced apart.

To hold the wires of the different layers in place and prevent them from unwinding, I apply a binding or reinforcement strip 18 of the character shown in detail in Figs. 4 and 4a. The binding strip 18 is formed with a central groove or recess 19 adapted to embrace the wire of the outer helix 17. The width of the strip is slightly less than the center to center spacing of the convolutions of helix 17. The strip 18 when applied to the casing is wound in the same direction and with the same pitch as the helix 17, as shown in Fig. 1. The strip may also be knurled or formed with transverse depressions 20 to register with and fit upon the wires of the second layer 16.

As a strip 18 is wound upon the casing it is

preferably preformed to a smaller diameter than the outside diameter of the casing so that it will tightly hug the casing. Such binding or reinforcement may be applied at predetermined points on a continuous length of casing and the casing may then be severed at such points by sawing or cutting through the binding so as to leave a part of the binding on each of the severed ends. Since the binding is preformed it will hold the layers temporarily against uncoiling or spreading. The hold of the binding strip will be increased if the parts are so proportioned as to effect engagement of the transverse depressions 20 with the wires of layer 16.

15 Each end of the casing is now subjected to a swedging operation, an arbor 21 being inserted in the end under treatment. The swedging operation compresses the binding from the condition illustrated in Fig. 1 to that illustrated in Fig. 2, 20 in which it will be observed that the binding strip is forced into intimate contact with the casing, substantially enveloping the wire of helix 17 and being to a certain extent molded upon the wires of the second layer 16. The swedging operation also causes the helix 17 to be partly embedded in corrugations of layer 16, thereby tying the wires of layer 16 together, and since the helix 17 is also embedded in the binding strip 18 the latter is thus firmly anchored to the layer 25 16 as well. It will also be observed from an inspection of Fig. 2 (which shows the finished casing after the arbor 21 has been withdrawn) that in the swedging operation the strip 18 is spread so that adjacent convolutions are in tight contact 30 and the result is a substantially continuous sleeve forming a reinforcement on the end of the casing. This sleeve is preferably of such thickness that an annular groove 22 may be formed therein for attachment purposes. Also the sleeve may 35 be threaded, if desired, as shown at 23 (Fig. 5).

40 The structure shown in Figs. 5, 6 and 6a differs from that already described mainly in that a binding strip of different cross-section is employed. This binding strip which is indicated by the reference numeral 25 is of the same width as the binding strip 18 but instead of having a central groove is formed with two quarter-circle grooves 26 along each margin which are adapted to engage adjacent convolutions of the layer 17.

45 Between the grooves 26 the inner face of the strip is formed with depressions 27 adapted to fit upon the wires of layer 16. Fig. 5 shows the strip after it has been applied to the casing and swedged thereon. As explained above, this reinforcement may be formed with threads 23 for attachment purposes, or, if desired, it may be formed with an attachment groove 22. When the binding strip is swedged upon the casing the convolutions of layer 17 are embedded in the 50 binding strip at the junction between adjacent convolutions of the strip. In this case, as in that described above, the swedging operation serves to cause partial embedment of layer 17 into layer 16 and also partial embedment of layer 16 55 and binding strip 25 so that the parts are all rigidly united.

60 In the construction shown in Figs. 7, 8 and 8a a still different section of binding strip is employed. This strip which is indicated by the reference numeral 30 is formed with a groove 31 along one margin only, while the opposite margin is rounded, as shown at 33. The groove 31 is adapted to receive the wire of layer 17 and transverse depressions 32 in the face of the strip are 65 adapted to receive the wires of layer 16. After 70 75

the strip 30 has been swedged upon the casing the parts assume the position shown in Fig. 7 with the wire of layer 17 embedded in one edge of the strip 30. This strip may be formed with threads 23 or annular groove 22 for attachment purposes.

In Fig. 7 I show still another form of attachment fitting. This consists of a sleeve 34 which is fitted over the binding 30 and then is swedged thereon. The sleeve is thus made fast to the 10 reinforcement 30 and hence to the casing by frictional engagement therewith and also by partial embedment. Such embedment is due to the fact that the strip is formed with a rounded edge 33 so as to provide a groove between adjacent 15 convolutions of the strip 30 into which the metal of the sleeve 34 is forced by the swedging operation. The sleeve 34 may be provided with an annular groove 35 for attachment purposes.

Another means of attaching the casing to a 20 fixed support is shown in Figs. 9 and 10. The structure of the casing and reinforcement corresponds to that shown in Figs. 1 and 2. The fixture to which the casing is attached consists of a clamp comprising a member 38 and a member 39. This clamp has a bore 40 formed between the members which is of the same diameter as the inside diameter of the casing at the point where it has been swedged. The bore has an enlargement 41 to receive the casing, and the latter is clamped between the members 38 and 39 by means of bolts 42. The casing serves usually as a guide for a rotary and/or sliding power transmitting element and there is the danger that the inner layer may present a sharp or jagged wire end which will engage said element, fraying the casing or causing a serious jam. To avoid this I bevel the inner layer of the casing, as indicated at 43, and provide an annular flange 44 on the members 38 and 39 at the junction of bore 40 and enlargement 41, this flange being beveled to fit the bevel 43. Thus, the end of the inner layer is bound and held in place by the flange 44.

Fig. 11 shows one end of the piece of casing 45 made of two helices of wire 45 and 46 respectively which are of triangular cross-section with the base of the triangle of wire 45 forming the inner face of the casing and the base of the triangle of wire 46 forming the outer face of the casing. 50 Upon this casing is wrapped a binding strip 47 which is of rectangular section. The wires 45 and 46 form right-hand helices whereas the strip 47 forms a left hand helix so that the joints between successive convolutions of the strip 47 are 55 disposed transversely to the joints between the convolutions of the helix formed from wire 46. The casing and binding strip are subjected to a swedging operation which binds the strip 47 tightly to the casing, forcing it into the crevices 60 formed between successive convolutions of the helix formed from wire 46. This serves to bind the strip 47 upon the casing and to form a substantially rigid sleeve portion at the end of the casing. While I prefer to reverse the binding 65 with respect to that of the helices formed from wire 45 and 46 I do not wish to limit myself to this arrangement, since it will be obvious that by using a binding strip which is much wider than the wire 46, such binding strip must be 7 wound with a greater pitch angle if adjacent convolutions are contiguous and consequently the joint between successive convolutions of the strip 47 cannot coincide with the joint between convolutions of wire 46 but must traverse such 7

joint and bind the convolutions of wire 46 together even though the lay be not reversed.

In Fig. 12 I show still another form of my invention in which the binding is applied directly 5 to a flexible casing consisting of a single wire helix 50. The end of this casing is bound with a strip 51 which may be of the same section as strip 47 and as in the structure shown in Fig. 11, the lay of the strip 51 is preferably although not necessarily reversed with respect to that of the helix 50. The casing and binding strip 51 are subjected to a swedging operation which forces the strip 51 into the crevices between adjacent convolutions of the helix 50, thus binding said 15 convolutions and forming a rigid sleeve at the end of the casing.

While I have described my method in connection with a disclosure of several forms of coiled wire casings, binding strips and end fittings produced thereby, it is to be understood that this disclosure and the specific description thereof and of my method as applied thereto, are to be taken merely as illustrative and not limitative of the method and its application to stranded structures 25 generally, and that I reserve the right to vary my method and apply it to produce different forms of tubular casings, conduits, shaftings, etc., without departing from the spirit and scope of my invention as clearly set forth in the following claims. In the claims, I employ the terms "tubular casing," "casing," "coil" and "helical coil" in their broad sense to include all equivalents to which my method may be applied.

I claim:

35 1. The method of producing flexible tubular casings from a continuous wire coil, which includes the steps of wrapping the wire coil with a metal ribbon at separate predetermined points on the coil, severing the coil at such points by cutting through the ribbon and the coil so as to form a plurality of tubular casings each having a metal ribbon binding at each end thereof, and swedging the ribbon upon the coil at each end of the casing.

45 2. The method of making flexible tubular casings from a continuous wire coil, which includes the steps of wrapping the wire coil with a metal ribbon at separate predetermined points on the coil, contouring the inner face of the ribbon before wrapping to fit the surface of the coil, severing the coil at such points by cutting through the ribbon and the coil so as to form a plurality of tubular casings each having a metal ribbon binding at each end thereof, and swedging the 55 ribbon on the coil at each end of the casing.

3. The method of making flexible tubular casings from a continuous wire coil, which includes the steps of wrapping the wire coil with a metal ribbon at separate predetermined points on the coil, contouring the inner face of the ribbon before wrapping to fit the surface of the coil, performing the ribbon during the wrapping to hug the coil, severing the coil at such points by cutting through the ribbon and the coil so as to form a plurality of tubular casings each having a metal ribbon binding at each end thereof, and swedging the ribbon on the coil at each end of the casing.

4. The method of making flexible tubular casings from a continuous wire coil structure composed of a plurality of layers, the outer layer consisting of an open coil, which includes the steps of wrapping a metal strip upon the coil structure at separate predetermined points thereon, forming a groove in the strip before wrapping to

receive the wire of said open coil, severing the coil structure at said points by cutting through the strip and the coil structure so as to form a plurality of tubular casings each having a metal strip binding at each end thereof, and swedging the strip on the tubular structure at each end of the casing.

5. The method of making flexible tubular casings from a continuous wire coil structure composed of a plurality of layers, the outer layer 10 consisting of an open coil, which includes the steps of wrapping a metal strip upon the coil structure at separate predetermined points thereon, forming a groove in the strip before wrapping to receive the wire of said open coil, 15 preforming the strip as it is wrapped to hug the coil structure, severing the coil structure at said points by cutting through the strip and the coil structure so as to form a plurality of tubular casings each having a metal strip binding at 20 each end thereof, and swedging the strip on the tubular structure at each end of the casing.

6. The method of making flexible tubular casings from a continuous wire coil structure composed of a plurality of layers, the outer layer 25 consisting of an open coil of reverse lay with respect to that of the next adjacent layer, which includes the steps of wrapping a metal strip upon the coil structure at separate predetermined points thereon, forming the metal strip before 30 winding with a longitudinal recess to receive the wire of said open coil and with transverse recesses to fit over the convolutions of said next adjacent layer, severing the coil structure at said points by cutting through the strip and the coil 35 structure so as to form a plurality of tubular casings each having a metal strip binding at each end thereof, and swedging the binding on the tubular structure at each end of the casing.

7. The method of making flexible tubular casings from a continuous wire coil structure composed of a plurality of layers with the outer layer 40 consisting of an open coil, which includes the steps of forming a binding strip of a width slightly less than the center to center spacing of the convolutions of said open coil and with a longitudinal recess to receive the wire of said open coil, wrapping the strip upon the coil structure at separate predetermined points thereon with the wire of said open coil in said recess, severing the coil structure at said points by cutting the strip and the coil structure so as to form a plurality of tubular casings each having a metal strip binding at each end thereof, and swedging the strip on the tubular structure at each end 50 of the casing to effect mutual embedment of the wire and strip and spread the turns of the strip into mutually contiguous relation.

8. The method of making flexible tubular casings from a continuous wire coil structure composed of a plurality of layers with the outer layer 55 consisting of an open coil, which includes the steps of forming a binding strip of a width slightly less than the center to center spacing of the convolutions of said open coil and with a longitudinal recess to receive the wire of said open coil, wrapping the strip upon the coil structure at separate predetermined points thereon with the wire of said open coil in said recess, performing the strip as it is wrapped to hub the 60 coil structure, severing the coil structure at said points by cutting the strip and the coil structure so as to form a plurality of tubular casings each having a metal strip binding at each end thereof, and swedging the strip on the tubular 65 structure.

structure at each end of the casing to effect mutual embedment of the wire and strip and spread the turns of the strip into mutually contiguous relation.

5. 9. The method of forming flexible tubular casings from a continuous wire coil structure composed of a plurality of layers with the outer layer consisting of an open coil, which includes the steps of preparing a metal strip of a width 10 slightly less than the center to center spacing of the convolutions of said outer coil and forming the strip with a recess along each margin thereof, winding the strip at predetermined points upon the coil structure between the convolutions 15 of said open coil and with said convolutions partly embraced in said recesses, severing the coil structure at said points by cutting through the strip and the coil structure so as to form a plurality of tubular casings each having 20 a metal strip binding at each end thereof, and swedging the strip on the tubular structure at each end of the casing so as to spread the convolutions of the strip into mutually contiguous relation and completely envelop the convolutions 25 of said open coil and also so as to embed the strip in the layer next adjacent said open coil.

10. The method of binding an end of a coiled wire casing which includes the steps of wrapping a metal strip helically about the casing at said 30 end, contouring the inner face of the strip before wrapping so that it will fit upon the coiled wire surface of the casing, and swedging the wrapping upon the casing so as to form a ferrule thereon.

11. The method of binding an end of a coiled wire casing which includes the steps of wrapping a metal strip helically about the casing at said 35 end, contouring the inner face of the strip before wrapping so that it will fit upon the coiled wire surface of the casing, preforming the strip as it is being wrapped about the casing so that it will hug said casing closely, and swedging the wrapping upon the casing so as to form a ferrule thereon.

12. The method of binding an end of a tubular casing comprising at least one coil of wire, which includes the steps of wrapping a metal strip helically upon the coil at said end but with a reverse lay with respect to that of said coil, 45 and swedging the wrapping upon the casing to force the material of the wrapping into the interstices between the convolutions of said coil and form a ferrule on the casing.

13. The method of binding an end of a tubular 50 coiled wire casing, which includes the steps of wrapping a metal strip helically upon the coiled wire casing at said end but with a reverse lay with respect to that of said coiled wire casing, transversely grooving the inner face of the strip before wrapping so that it will fit upon the coiled wire 55 surface of the casing, and swedging the wrapping upon the casing to force the material of the wrapping into the interstices between the convolutions of said coiled wire casing and form a ferrule on the casing.

14. The method of producing desired lengths 60 of stranded wire structures and reinforcing the ends thereof, which consists in wrapping wire bindings on a continuous length of stranded wire structure at points spaced at distances corresponding to said lengths, and of sufficient inherent strength to preserve the integrity of the 65 stranded wire structure when severed at said points, severing the wire bindings and stranded wire structure at such points to form a plurality

of such stranded structures of desired length each having a wire binding on each end thereof, and swedging the wire bindings onto such stranded structures.

15. The method of producing desired lengths of 5 stranded wire structures from a continuous length of stranded wire and reinforcing the ends thereof, which consists in wrapping separate wire bindings at spaced predetermined points on said stranded wire structure, and of sufficient inherent strength to preserve the integrity of the stranded wire structure when severed at said points, and severing the wire bindings and stranded wire structure at such points to form such desired lengths of stranded wire structures 10 each having a wire binding on each end thereof.

16. The method of producing desired lengths of 15 stranded wire structures provided with end fittings, which consists in constricting upon a continuous length of a stranded wire structure, 20 at points spaced at distances corresponding to such lengths, members of sufficient inherent strength to preserve the integrity of said stranded wire structure when severed, severing the members and stranded wire structure at such points 25 to form a plurality of such stranded wire structures, each having a constricting member on each end thereof, and swedging said members on such stranded wire structures to form end fittings.

17. The method of producing desired lengths 30 of coiled wire structures provided with end fittings, which consists in constricting, at points on a continuous length of a coiled wire structure spaced at distances corresponding to such lengths, members of sufficient inherent strength to prevent uncoiling of said coiled wire structure when 35 severed, severing the members and coiled wire structure at such points to form a plurality of such coiled wire structures, each having a constricting member on each end thereof, and swedging said members on each end of such coiled wire structures to form end fittings.

18. The method of binding an intermediate portion of a continuous helically coiled stranded structure which includes the step of wrapping a 45 metal strip helically about said structure and preforming the strip as it is being wrapped about such structure so that it will hug such structure closely.

19. The method of binding the end of a helically 50 coiled stranded wire structure which includes the step of wrapping said end with a metal strip of sufficient inherent strength to prevent uncoiling of said structure and in preforming said strip as it is being wrapped about the structure so that 55 it will hug said structure closely.

20. The method of binding an end of a coiled wire structure comprising inner and outer coiled wire layers, the outer layer comprising spaced convolutions, which includes the steps of wrapping 60 a metal strip helically about the end of said structure and in contouring the inner face of the strip so that it will fit over the convolutions of said layers.

21. The method of binding an end of a coiled 65 wire structure comprising inner and outer coiled wire layers, the convolutions of the outer layer being spaced, which includes the steps of wrapping a metal strip helically about an end of the structure and in contouring said strip to fit between the convolutions of both layers.

22. The method of binding an end of a coiled 70 wire structure comprising inner and outer layers of coiled wire, the convolutions of the outer layer being spaced, which includes the steps of wrap-

ping a metal strip helically about an end of the structure between the convolutions of said outer layer and in contouring the inner face of said strip to fit on and between the convolutions of said inner layer.

23. The method of binding an end of a coiled wire structure comprising inner and outer layers of coiled wire structures, the convolutions of the

outer layer being spaced, which includes the steps of compacting an attachment member into the spaces between the convolutions of the inner and outer layers, and impacting the convolutions of the outer layer into the spaces between the convolutions of the inner layer.

OTTO J. BRATZ.
